PACKAGING CONTAINER

Stanford W. Bird, Salt Lake City, Utah, assignor to
Plastronics Corporation, Salt Lake City, Utah

Filed Jan. 7, 1971, Ser. No. 104,847

Term of patent 14 years

Int. Cl. D9—03

U.S. Cl. D9—231

FIG 1

FIG 2

FIG 3

FIG. 4

FIG. 1 is a top plan view of a packaging container showing my new design;

FIG. 2 is a bottom plan view;

FIG. 3 is an enlarged perspective view taken from one side and slightly above the packaging container at the front; and

FIG. 4 is a side elevational view on a scale larger than that of FIG. 3.

I claim:

The ornamental design for a packaging container, substantially as shown.
